Primary Examiner — Cynthia M Chin(74) *Attorney, Agent, or Firm* — Fitzgerald IP Law; John K. Fitzgerald(57) **CLAIM**

The ornamental design for a toy house, as shown and described.

DESCRIPTION

FIG. 1 is a perspective view showing the roof, front, a side, and a portion of the interior of a toy house, showing my new design;

FIG. 2 is a rear perspective view of the toy house of FIG. 1 showing the roof, a side, and a portion of the interior, thereof;

FIG. 3 is a frontal view thereof;

FIG. 4 is a rear view thereof;

FIG. 5 is an overhead view thereof;

FIG. 6 is a right side view thereof; and,

FIG. 7 is a left side view thereof.

The broken lines shown are included for the purpose of illustrating portions of the article which form no part of the claimed design.
